FOREIGN PATENT DOCUMENTS

WO DM213517 12/2020

Primary Examiner — Cynthia R Underwood

(74) *Attorney, Agent, or Firm* — McAndrews, Held & Malloy, Ltd.

CLAIM

The ornamental design for a tie down bracket for a trailer frame, as shown and described.

DESCRIPTION

FIG. 1 is a top and front perspective view of a tie down bracket for a trailer frame showing my new design;

FIG. 2 is a front elevation view thereof;

FIG. 3 is a rear elevation thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a bottom and rear perspective view thereof.

The dashed broken lines in the figures illustrate portions of the tie down bracket for a trailer frame that form no part of the claimed design.

1 Claim, 7 Drawing Sheets
